UNITED STATES PATENT OFFICE.

HYMAN STARR, OF NEW YORK, N. Y., AND FRANK L. NICHOLS, OF STAMFORD, CONNECTICUT; SAID NICHOLS ASSIGNOR TO SAID STARR.

MACHINE FOR SEWING LOOPED FABRICS.

No. 809,855.

Specification of Letters Patent.

Patented Jan. 9, 1906.

Application filed May 12, 1904. Serial No. 207,649.

To all whom it may concern:

Be it known that we, HYMAN STARR, of New York, borough of Manhattan, in the State of New York, and FRANK L. NICHOLS, of Stamford, in the county of Fairfield and State of Connecticut, have invented certain new and useful Improvements in Machines for Sewing Looped Fabrics, of which the following is a specification.

- 10 This invention relates to machines for sewing looped fabrics, and more particularly to machines of the point-ring type designed for the finishing or interconnection of knit webs provided at one or more edges with a series of unconnected loops, and among the objects of the invention is the provision of a machine of this class in which the operative parts are so arranged as to permit free access to the needle and looper and at the same time to all 15 parts of the point-ring in order that the output of the machine will be materially increased, owing to increased facility and consequent rapidity with which the sewing operation can be effected.
- 20 The invention also aims to provide a machine in which the motion-transmitting mechanism is so arranged as to be readily accessible for lubrication, but nevertheless out of the way of the operator or operators while 25 working upon the machine, so that the liability of accident caused by contact with the motion-transmitting mechanism is thereby decreased in a marked degree.

With these and other advantages in view the 30 invention consists in the novel features and combinations of parts to be hereinafter described, and finally pointed out in the claims.

In the accompanying drawings, Figure 1 is a side elevation of our improved machine for 35 sewing looped fabrics. Fig. 2 is a top view of the machine shown in Fig. 1. Fig. 3 is a vertical transverse section on line 3 3, Fig. 2. Fig. 4 is a detail elevation, on an enlarged scale, of a portion of the mechanism for driving 40 the looper-point ring. Fig. 5 is a vertical transverse section on line 5 5, Fig. 4. Fig. 50 5 is a top view, on a larger scale than Fig. 2, of a portion of the mechanism. Fig. 7 is a vertical longitudinal section on line 7 7, Fig. 6. Fig. 8 is a front elevation of a portion of the mechanism adjacent the needle. Fig. 9 is a vertical transverse section of the clutch-operating mechanism, taken on line 9 9, Fig. 6. Fig. 10 is a vertical longitudinal section of the

same, taken on line 10 10, Fig. 6; and Fig. 11 is an enlarged vertical longitudinal section of the point-ring brake, taken on line 11 11, Fig. 2.

Similar letters of reference indicate corresponding parts.

Referring to the drawings, A indicates a suitable standard upon which the operating mechanism of the machine is supported. A yoke *a* is mounted on the top of the standard A and secured thereto by a set-screw *n*, said yoke supporting the bed-plate B of the machine. Said bed-plate is provided near its periphery with a flange *a'*, which forms a bearing for a looper-point ring *a''*. The looper-point ring is secured rotatably to the bed-plate by means of a stay-ring *a''*, which is secured by screws to the bed-plate and which projects into an annular recess formed above a flange *a''* at the interior circumference of the looper-point ring. The looper-point ring *a''* is provided at its under side with rack-teeth *a''*, which are received in a groove *a''* of the bed-plate and which are engaged by a pinion *a''*, which is mounted on a shaft *a''*, supported in bearings below the bed-plate. The shaft *a''* receives intermittent rotary motion by means of a pawl *a''*, which is mounted eccentrically upon the driving-shaft *b* and which engages a ratchet-wheel *b'*, secured to the opposite end of the shaft *a''*. The driving-shaft *b* is supported in bearings *d''* and *e'* on the bed-plate B and is disposed diametrically of the latter, being of such a length as not to extend at either end over the point-ring. The shaft *b* is provided with a pulley *d'*, to which rotary motion is transmitted by a driving-belt from an overhead shaft in the usual manner. The looper-points *b''* are secured in position radially of the bed-plate and point-ring by any suitable means, such as segmental clamping-bars *b''*, which clamp the inner angularly-bent ends of said points between themselves and the point-ring, as indicated in Figs. 5 and 7.

The needle *b''* is mounted on the lower end of a needle-arm *b''*, which is fulcrumed at its upper end to a stationary bracket *b''*, supported upon the bed-plate B. The needle-arm *b''* is actuated by means of a connecting-rod *b''*, which is strapped to an eccentric on the driving-shaft *b*, as indicated in Figs. 6 and 7. The thread is supplied from a bobbin or spool *b''*, which is mounted on a spindle on the bed-plate, passed through a suitable guide *b''* at the upper part of the spindle, then beneath

a guide-pin c of the bracket d^7 , through a tension-regulating device c' , around the lower end of the needle-arm b^5 , and thence through the needle-eye, which is in proximity to the 5 point of the needle. Coöperating with the needle is a looper-hook c^2 , which is actuated by means of a universally-pivoted operating-arm c^3 , said arm being pivoted to swing vertically upon a suitable bracket c^4 and the 10 latter pivoted to swing horizontally upon the bed-plate, as clearly shown in Figs. 6 and 7. The arm c^3 is provided with a laterally-projecting pin c^{14} , which is held in contact with the face of a suitably-formed cam c^5 , secured 15 upon the driving-shaft b intermediately of the length thereof and in proximity to the center of the bed-plate, said pin being retained in engagement with the cam by a helical spring c^6 , interposed between the arm c^3 and the 20 upper end of a post c^7 on the bed-plate.

A stationary guard c^8 is arranged at a point adjacent to the ends of the looper-points below the needle, so as to prevent the forcing of the loops of the fabric off the points by the needle 25 during the operation of looping. The guard c^8 is supported by any suitable means—such, for instance, as a curved bracket-arm c^9 , which extends outwardly over the looper-points and below the same sufficiently to clear the needle 30 b^4 and which is secured at its inner end to the stationary ring a^3 or other suitable point of support.

To prevent the momentum of the intermittently-rotating looper-point ring from being 35 carried beyond the point to which it is moved by its actuating pawl-and-ratchet device, a brake mechanism is provided, which consists of a segmental plate m , that is secured by its shank by a screw s to the bed-plate B and by 40 a screw S' to the stay-ring a^3 , said plate m being provided at its outer end with a shoe y of felt or other material, which bears on the looper-point ring a^2 , as shown in Figs. 2 and 11.

45 Upon the driving-shaft b is splined one member d of a clutch, which member is adapted to engage the opposite member of the clutch on the driving-pulley d' . The clutch member d is actuated longitudinally upon the driving-shaft b by means of an operating-rod d^2 , suitably mounted in one bearing d^3 of the shaft and provided with a handle d^4 . When the rod d^2 is moved in outward direction toward the adjacent end of the shaft by means of 50 the handle d^4 , the clutch member d is disengaged from the opposite clutch member, and thereby the pulley d' permitted to revolve upon the shaft without driving the machine. When the clutch-operating rod d^2 is moved 55 inwardly toward the pulley, the clutch member d is carried into engagement with the clutch member of the pulley, and thereby the shaft and pulley coupled for driving the machine. The clutch member d is retained in either position to which it is moved by means 60

of a pin d^5 , which is actuated toward the operating-rod d^2 by means of a spring d^7 and adapted to engage either of two grooves d^6 of the rod d^2 , and thereby lock the operating-rod and the clutch member either in or out 70 of engagement with the pulley. At its opposite end the driving-shaft b is provided with a crank-handle d^8 for operating the machine by hand whenever such operation should be desirable. 75

All the operating and motion-transmitting parts with the exception of the shaft a^8 , which is located below the bed-plate and in the space formed by the yoke a , are mounted on the bed-plate and within the stationary stay-ring a^3 , so as to be fully within sight for lubrication, adjustment, and repairs. The oscillating needle, the looper, and the stationary guard are located at a point of the bed-plate and looper-point ring at right angles to the 80 driving-shaft in such a manner that free access is given to the looper-point ring at its entire circumference for looping flat and circular fabrics, one operator being located in front of the looping devices and another operator at the opposite side for placing the fabric on the looper-points and feeding them then on to the operator at the looping devices. 85

The motions of the looper-point ring, needle, and looper and the manner of coöperation of 90 the needle and looper are substantially the same as in the looping-machines heretofore constructed. The fabric having at its edge the unconnected loops which are to be connected is placed upon the machine by placing 95 the successive loops upon the successive looper-points. The looper-point ring is rotated intermittently by means of the pawl-and-ratchet mechanism previously described, the intermittent motion taking place while the 100 needle is oscillated in backward direction—that is to say, toward the center of the machine. The looper-point ring having been moved so as to bring a fresh loop into the path 105 of the needle, the latter advances, enters the loop so as to carry the thread through the same, and then withdraws, the further operations during the advance of the needle and thereafter being performed coöperatively 110 therewith by the hook, said steps of intermittent feed of the point-ring and advance of the needle and coöperation of the hook being successively repeated, whereby a continuous edge 115 is formed on the open loops of the fabric.

120 The following are some of the advantages as compared with the machines for sewing looped fabrics heretofore in use:

First. A greater degree of accessibility is provided to all parts of the machine and in particular to those parts adjacent the needle, 125 whereby the operator is enabled to take his position directly in front of the needle and looper.

Secondly. When joining or sewing together two separate knit fabrics, two operators may 130

be continuously and simultaneously employed on one machine. In such case one operator is located directly in front of the hook and needle and the other at a point diametrically opposite thereto. The latter operator places the loops of one fabric upon the looper-points and the operator at the needle subsequently places the loops of the second fabric upon the same points next to the loops of the first fabric, so that the needle passes through both loops, and thereby connects the two fabrics.

Thirdly. The looping of flat and circular fabrics can be accomplished with great facility and without breaking of the thread in one continuous operation, forming a perfectly continuous edge. The loops of the fabric are applied continuously upon the looper-points at one side of the needle and as fast as looped are removed at the opposite side of the needle, so that by a circular movement of the tubular fabric the continuous looping of the entire fabric is accomplished. When a ribbed border is to be joined to a circular web, two operators may be simultaneously employed. The first, located diametrically opposite to the needle, performs the primary operation of picking up and placing the flat-ribbed border upon the looper-points, while the other, seated at the needle, handles the circular web, joins the same to the ribbed border, and sews these together in one continuous operation.

Having thus described our invention, we claim as new and desire to secure by Letters Patent—

35 1. In a machine for sewing looped fabrics, the combination of a bed-plate provided with an opening, a rotatable looper - point ring guided on said bed-plate and provided on its lower surface with a plurality of gear-teeth,

a driving-shaft mounted on said bed-plate 40 within said point-ring and above said opening, a second shaft mounted in bearings beneath said bed-plate and carrying a ratchet-wheel, a gear-wheel on said second shaft meshing with the gear-teeth on said point-ring, an eccentrically - mounted pawl on said driving-shaft extending downwardly through the opening in the bed and engaging said ratchet-wheel, a needle and a looper adjacent said looper-point ring, and means for transmitting 45 movement from said driving-shaft to said needle and looper.

2. In a machine for sewing looped fabrics, the combination of an upright supporting-standard, a yoke supported on the same, a 55 bed-plate mounted on the yoke, a driving-shaft journaled on the bed-plate, a looper-point ring guided in the bed-plate and provided with a circular rack at the under side, a second shaft supported in bearings at the 60 under side of the bed-plate and passing through the yoke, a pinion on the second shaft meshing with the circular rack on the looper-point ring, means for transmitting intermittent rotary motion from the driving-shaft to the 65 second shaft, an oscillating needle, a laterally-reciprocating looper, and mechanism supported on the bed-plate for transmitting motion to the needle and looper.

In testimony that we claim the foregoing as 70 our invention we have signed our names in presence of two subscribing witnesses.

HYMAN STARR.
FRANK L. NICHOLS.
